BAFFLE PLATE FOR USE IN TUBE TYPE
HEAT EXCHANGERS

John E. Weiks, Seattle, Wash.

Application May 29, 1947, Serial No. 751,203

2 Claims. (Cl. 257—236)

1

This invention relates to baffle plate means for use in a tube type heat exchanger and my present invention is in the nature of an improvement over the baffle plate means disclosed in my co-pending patent application Serial No. 596,273, filed May 28, 1945, now Patent No. 2,513,124.

An object of this invention is to provide a baffle plate having resilient edge portions shaped so that they will maintain close contact with the walls of a housing in which they are installed irrespective of irregularities in said housing wall.

Another object is to provide a baffle plate in which the capacity of the edge portions thereof to maintain close contact with the walls of a housing will not be destroyed by repeatedly removing the baffle and tube assembly by which it is carried from and replacing the same in the housing.

Another object is to provide a baffle plate which will not wear a housing in which it is installed when subjected to vibration.

A further object is to provide a baffle plate of resilient metal having curved edge portions adapted to contact and conform to the shape of the walls of a housing in which the baffle is installed.

The baffle plate herein disclosed is well adapted for use in water coolers for marine engines where the cooler is subjected to constant vibration when the engine is running but obviously said baffle plate can be advantageously used in other structures wherein a flow of liquid is to be controlled.

Other objects of the invention will be apparent from the following description and accompanying drawings.

In the drawings Figure 1 is a longitudinal medial section, with parts in elevation, showing a marine engine cooler having baffle plates constructed in accordance with this invention.

Fig. 2 is a vertical sectional view on a larger scale than Fig. 1, taken substantially on broken line 2—2 of Fig. 1.

Fig. 3 is a fragmentary detached perspective view showing a baffle plate constructed in accordance with this invention.

Fig. 4 is a fragmentary detached sectional view on a larger scale than the preceding figures showing an edge portion of this baffle plate in contact with a housing wall.

Fig. 5 is a fragmentary detached perspective view of a baffle plate of modified form.

Like reference numerals designate like parts throughout the several views.

For the purpose of illustration I have shown this baffle plate as applied to a marine engine

cooler in which fresh water is cooled by the use of salt water and the fresh water thus cooled is used for cooling the engine.

The marine engine cooler shown in Figs. 1 and 2 comprises a shell or housing 10 having two tube sheets 6 and 7 fixedly connected with opposite ends thereof. Two bowl shaped manifolds 8 and 9 are secured to the respective tube sheets 6 and 7 at the two ends of the housing 10. A plurality of tubes 11 extend lengthwise within the housing 10 and have their end portions extended through and sealed in the tube sheets in any suitable manner to provide water tight joints. A galvanic retarder 12 is positioned within the manifold 9 and a flood plate 13 is positioned within the manifold 8. Liquid inlet and outlet conduits 14 and 15 are connected with the respective manifolds 9 and 8 so that liquid of one temperature, such as cool sea water, can be circulated through the tubes 11. The housing 10 is provided with a water inlet opening 16 and a water outlet opening 17 so that another liquid such as warm fresh water, can be circulated through the housing 10 around the tubes 11.

25 A marine engine to be cooled can be connected by suitable hydraulic circuit means with the inlet opening 16 and outlet opening 17. Preferably a receptacle 18 and a thermostatic control device 19 are included in the hydraulic circuit means so that liquid to be cooled can travel through thermostatic means 19, receptacle 18, opening 16, housing 10, where it is cooled, and then out through opening 17.

Any desired number of baffle plates made in accordance with this invention can be used in the housing 10 to direct the flow of liquid therethrough. Two baffle plates 20 and 21 are shown in the housing 10. Each baffle plate 20 and 21 has a resilient curved edge portion 22. Each curved edge portion 22 is preferably formed and shaped so that the curved outer wall portion thereof rests against and makes contact with the wall of the housing 10 and the marginal edge 23 thereof is clear of the housing wall. This obviates contact of a sharp corner of the baffle plate with the housing wall and provides a baffle edge portion that will conform more closely to a housing wall of irregular shape than will a baffle edge portion in which the edge proper engages the housing wall.

40 Each baffle plate is recessed or cut away at one end, see Fig. 1, to provide a passageway 24 through which liquid may flow from one compartment to another in the housing 10.

45 The baffle plates 20 and 21 extend longitudinally

of the housing 10 between the tubes 11 to direct liquid back and forth from one end to the other of said housing. To compensate for inequalities in longitudinal expansion and contraction between the baffle plates 20 and 21 and the housing 10 the length of each baffle plate is preferably slightly less than the distance between the two tube sheets 6 and 7. When the baffles are installed in the housing the slight clearance thus provided for is left at the recessed end of each baffle, see 10 Fig. 1, and the other or non-recessed end thereof is positioned in close contact with the adjacent tube sheet to prevent a leakage of liquid between it and said tube sheet. The resilient edge portions 22 of the baffles will bind tightly enough 15 against the walls of the housing 10 to prevent longitudinal displacement of baffles installed as above described even under vibration and to insure that the non-recessed ends of said baffles will remain in contact with the adjacent tube 20 sheet.

For use in marine engine coolers where the baffles are of small size it has been found satisfactory to make each baffle of a single integral piece of twenty-eight gauge spring brass or Phosphor bronze. Baffles of larger sizes can be more economically made, as shown in Fig. 5, by using a less expensive metal 25 for the main body portion of the baffle and riveting or otherwise securing to opposite edges thereof resilient curved edge members 26 of thin metal that are shaped like the edge portions 22 previously described.

The two resilient edge portions 22 of each baffle extend sidewise in the same direction from the plane of the baffle. When these baffles are installed in a housing 10 they are preferably positioned so that the curve of the edge portions 22 of each baffle conforms in a general way to the curve of that portion of the housing wall with which they make contact. Thus in Fig. 2 the edge portions of the baffle plate 20, which is above the horizontal center plane of the housing 10 curve downwardly and the curved edge portions of the lower baffle 21, which is below that plane, curve upwardly.

A housing 10 of the type shown in Figs. 1 and 2 is usually not accurately made and the walls thereof are somewhat irregular in shape. The resilient edge portions of baffles made in accordance with this invention will conform fairly well to these irregularities thus making a substantially liquid tight seal between the edges of the baffle and the housing wall. This materially increases the efficiency of a marine cooler of the type illustrated as it tends to prevent the liquid from by-passing the edges of the baffles and taking a short course through the housing 10.

The resilient edge portions of the baffles will maintain a constant and even pressure against the side walls of the housing and even when the structure is subjected to vibration there will be substantially no relative movement between the baffles and the housing walls or between the baffles and any tubes 11 they may contact. Thus wear of the baffles on the housing 10 and tubes 11 is reduced to a minimum.

The baffles and tube assembly can repeatedly be removed from and replaced in the housing 10 without impairing the efficiency of the baffles.

The foregoing description and accompanying drawings clearly disclose a preferred embodiment of my invention but it will be understood that changes can be made within the scope of the following claims.

I claim:

1. In a heat exchanger, a cylindrical housing; fluid inlet and outlet means connected with said housing; tubes extending longitudinally of said housing; fluid inlet and outlet means connected with said tubes; a plane flat baffle plate positioned parallel to and to one side of the axis of said housing and disposed between said tubes and supported by said tubes and having an end thereof spaced from an adjacent end wall of the housing, said baffle cooperating in defining a path of flow in said housing; and integral curved resilient edges on said baffle plate resiliently and conformably engaging the cylindrical walls of said housing, the curvature of said resilient edges being toward the axis of the housing and conforming in a general way to the curvature of the portions of the cylindrical housing wall engaged thereby.

2. In a heat exchanger, a cylindrical housing; fluid inlet and outlet means connected with said housing; tubes extending longitudinally of said housing; fluid inlet and outlet means connected with said tubes; plane flat resilient baffle plates in said housing positioned to one side of the axis of said housing and disposed between said tubes and supported by said tube, portions of the ends of successive baffle plates being alternately spaced from the end walls of said housing providing for a flow of liquid back and forth in the spaces between said baffle plates; and integral curved resilient lateral edge portions of the same thickness as said baffle plates provided on said baffle plates resiliently and conformably engaging with the curved inside walls of said housing, the curvature of said resilient edge portions being toward the axis of the housing and conforming in a general way to the curvature of the housing walls and the extremities of said curved resilient edge portions being inturned sufficiently far so that they are clear of the housing wall when the outer curved surfaces of said curved lateral edge portions are in engagement with the housing wall, whereby wear between said curved lateral edge portions and said housing wall is reduced to a minimum.

JOHN E. WEIKS.
